UNITED STATES PATENT OFFICE.

JOHN RANCEVAU, OF CINCINNATI, OHIO, ASSIGNOR OF ONE-HALF TO
WM. DISNEY, OF SAME PLACE.

CAR-COUPING.

SPECIFICATION forming part of Letters Patent No. 359,813, dated March 22, 1887.

Application filed April 10, 1885. Serial No. 161,846. (No model.)

To all whom it may concern:

Be it known that I, JOHN RANCEVAU, of the city of Cincinnati, in the county of Hamilton and State of Ohio, have invented certain new and useful Improvements in Car-Couplings, of which the following is a specification.

My invention relates to that class of car-couplings known as "automatic" car-couplings.

10 The various features of my invention and their objects and advantages, when used either separately or together, will be apparent from the following specification.

In the accompanying drawings, making part 15 of this specification, Figure 1 is an end view of my invention, showing the coupling in position and locked ready to receive the coupling attached to the other car to be coupled. Fig. 2 is an end view of my invention, showing 20 the coupling unlocked ready to release the coupling of the car which would be attached to it. Fig. 3 is a top view of my invention. Fig. 4 is a top view of my invention, the top plate being removed to show the interior construction; and Fig. 5 is a view in perspective 25 of the coupling-head and coupling-head bar.

A represents the casting preferably made of cast-steel, but may be made of cast-iron or other suitable material. This casting A is 30 placed between the two plates A' A''. The top plate, A', and bottom plate, A'', with the casting A between them, are securely fastened together in any suitable manner, preferably by rivets a. The top and bottom plates, A' A'', 35 at their forward ends, widen, and are of peculiar shape, preferably of that shape shown in the drawings, and tapered toward a point, a', so that when the couplings approach each other they will more easily pass over the incline a' and lock.

40 Through the front end of the head or forward portion, B, of the coupling is passed the rivet a'', around which is placed the sleeve or collar a''. This collar is placed around the 45 rivet to make a bearing-surface and strengthen the plates at this point.

The plates may be strengthened in any suitable manner; but this collar and rivet is the preferable mode.

50 The casting A contains the pocket b and

hole or opening b'. Within the head B of the draw-bar is placed and suitably secured, preferably by bolt or pin connection b² b³, the coupling-head D. The coupling-head D is of peculiar shape, as shown in Fig. 5, and on 55 each side its face d has the lips d' d''. These lips may extend upward and downward any suitable distance to conform to the varying height of the platforms used by different railroads on their passenger and freight cars, so 60 as to catch and lock with the couplings of these different cars. This coupling-head is preferably made of steel. The coupling-head is cut away at d², or otherwise suitably formed, to give room for the usual coupling-link, which 65 may be used, if desired, the hole a² being present for the coupling-pin.

The sliding head-bar E, which works forward and backward in the pocket b as the car is being coupled or uncoupled, occupies the 70 space in the head B directly in front of the casting A, and at its forward end is formed into the head E'. This head E' has two ears, e e, between which fits and is loosely pivoted by pivot-pin e' the neck e² of the coupling-head D. This makes a joint similar to a knuckle-joint, and works easily and correctly every time the car is coupled or uncoupled. Around the sliding bar E is placed the coiled spring F, which throws the coupling-head back 75 to its position when the cars are being uncoupled. This spring can be omitted, and yet my device will perform its function of coupling and uncoupling automatically.

The pocket b in the casting A is preferably 80 widened at its forward end, h, so that the spring F may more easily play in the pocket, and the shoulders h' are also formed by the widening of the pocket to form a bearing for the spring F.

To the top plate, A', is suitably secured the lug in which the dog H is pivoted, preferably, as shown, by riveting the piece g, which carries the ears i i, to the top plate. To these ears i i is secured, by pin i', one end of the dog 95 H. The dog H works loosely upon this pin, and is guided into the hole or recess b', in which it works, by the guides b⁵ b⁵. The projection S of the dog H is beveled, so that it may more easily work against the end of the bar E. The 100

upper end of the dog H is divided into two prongs, *kk*, between which the pull-handle H' is secured. This handle at its lower end contains the slot *m*. Through this slot, and through the ears *i i*, passes the pin *i'*. This handle also contains the recess *n*, which recess fits over the pin *n'* in the sill of the car, and thus holds the handle in position when the coupling is being unlocked and cars being uncoupled. The slot *m* in the pull-handle H' is very useful. When it is desired to uncouple cars, the brakeman has hard work uncoupling them with the lever on the couplings now in use, as it works too hard. This difficulty is overcome by the use of my slot *m* in the handle H'. The brakeman takes hold of the handle H' and lifts, or, rather, jerks, it upward from the position it occupies in Fig. 1, and the handle moving upward, the lower end of the handle strikes the pin *i'*, and thus gives the dog H an impetus which readily brings the dog to the position shown in Fig. 2 and uncouples the cars. The chain H² equalizes the draft for pulling the draw-bar laterally.

The coupling works as follows: When it is desired to couple cars, the coupling stands in the position shown in Fig. 1. The car carrying a similar coupling is backed, and its coupling strikes and travels over the incline *a'*, and when it reaches the face *d* falls over and automatically locks with the coupling-head D, and the car is coupled. When it is desired to uncouple the cars, all that is necessary is to pull the handle H' until it assumes the position shown in Fig. 2. The dog H releasing its hold on the coupling-head rod E, the coupling will automatically unlock as soon as the engine moves forward.

One of the great advantages of my coupling lies in the fact that it can be readily and satisfactorily applied to the draw-bars now in

use, (as the Miller and others,) necessitating but slight change in the latter, and thus the expense of putting in new couplings is saved. The dotted lines in Figs. 3 and 4 show the position of the coupling-head when the coupling is unlocked. 45

While the various features of my invention are preferably used together, one or more of them may be used without the remainder, and 50 in car-couplers other than the one specifically herein set forth.

What I claim as new and of my invention, and desire to secure to secure by Letters Patent, is—

1. In a car-coupler, the combination of piece A, having pocket *b*, coupling-head D, coupling-head bar E, and pin or projection S, as and for the purposes set forth. 55
2. The combination of the coupling-head D, bar E, pocket *b*, dog H, having projection S, and slotted handle H', substantially as set forth. 60
3. The combination of the coupling-head D and coupling-head bar E, pivotally connected, and pocket *b* and dog H, substantially as and 65 for the purposes specified.
4. The combination of the coupling-head D, sliding bar E, pocket *b*, spring F, dog H, and handle H', with slot *m*, substantially as and for the purposes specified. 70
5. In a car-coupling, the handle H', having slot *m* and recess *n*, substantially as and for the purposes specified.
6. In an automatic car-coupling, the combination of a coupling-head and coupling-head 75 bar pivoted together, and the dog H, substantially as and for the purposes specified.

JOHN RANCEVAU.
